UNITED STATES PATENT OFFICE.

LOUISE NELSON, OF OAKLAND, CALIFORNIA.

CORSET-WAIST.

No. 897,646.

Specification of Letters Patent.

Patented Sept. 1, 1908.

Application filed March 5, 1906. Serial No. 304,423.

To all whom it may concern:

Be it known that I, LOUISE NELSON, a citizen of the United States, residing at Oakland, in the county of Alameda and State of California, have invented a new and useful Corset-Waist, of which the following is a specification.

My invention relates to a corset waist, the object of which is to support the breast and the stomach without lacing and without bones or steels.

Referring to the drawing, Figure 1 shows the corset waist, front view. Fig. 2, the corset side view. Fig. 3, the pattern, or the cut 15 of the waist. Fig. 4, is a view of the extension piece E which forms the support for the bust.

The main point in the invention is the fact that the bust is supported on a straight piece 20 or an extension having a straight edge which is sewed onto the curved edge of the front pieces. This extension (E) forms a complete shelf, having a curved edge on the top and is supported and kept from falling down 25 by means of straps going over the shoulder, by this means the bust is supported entirely from the shoulders by means of the straps (C), the breast simply resting on this straight shelf, which will form a corset even as a yoke, 30 without any waist whatever, the whole effect of this yoke arrangement which forms a perfect support for the bust is adjusted by means of a straight strap (K) going around the body beneath the arms and breast, and hooks 35 in front, the sewing on of the waist to this yoke is a decided advantage, for warmth and other reasons but not at all necessary to support the bust as there is no pressure on the waist line.

An important feature is the straight front 40 (A) without any dart or seams whatever, excepting the curved edge (F¹), which takes the place of all darts as it fits close to the body under the breast, very unlike any other 45 waist, as all corsets or corset waists shape from the large part of the bust, or the top of the bust, down to the waist, thereby causing a tightness in the waist line. While this waist is fitted to the shape of the body by 50 means of being curved out underneath of the breasts by the edge (F¹), causing no lacing or tightness in the waist line, and by reason of

it being straight on the front edge, it forms a perfect support as if lifting the stomach rather than pushing it down.

The back pieces Fig. 3 denoted by (B) are just the same as used in any ordinary dress and are not material in this pattern.

It is by the proper fitting and adjusting of the curved line (F¹) in Fig. 3 and the straight 60 line (F) in Fig. 4 which is sewed into the curved line (F¹) in Fig. 3 thereby forming a shelf, which supports the bust, and a straight strap going around the body which holds them in place, that the whole effect is brought 65 out, giving a perfectly natural shape, combined with comfort and the effect of a corset without wearing one, as there are no steels or bones.

The two front straps (C) and the two back 70 straps (D) are joined on the shoulder (G). Between the straps (C) and (C) the waist will be filled in with fabric (H) as that has nothing to do with the waist except to hold up the extension which supports the busts, preventing it from falling down by the weight of 75 the breasts. There will also be a straight strap sewed on to the bottom to support the stomach, also buttons sewed on to support the skirts. Also tabs on the front and back 80 for garters and the like.

I claim:

1. In a corset waist, a body piece with substantially straight fronts having outwardly curved upper edges, flexible segmental pieces 85 with straight inner edges, said straight edges being stitched to said curved edges of the fronts, and a plurality of supporting straps attached to the outer and inner ends of the segments.

2. In a corset waist, a body piece with substantially straight fronts having outwardly curved upper edges, flexible segmental pieces with straight inner edges, said straight edges being stitched to said curved edges and 95 forming substantially horizontal shelves of shallow depth, and straps converging from the outer ends of the segments, and from the back of the body piece, and meeting upon the shoulders.

LOUISE NELSON.
